UNITED STATES PATENT OFFICE

2,056,807

PLUMBING SYSTEM

William C. Shanley, Chicago, Ill., assignor to The
Imperial Brass Manufacturing Company, Chi-
cago, Ill., a corporation of Illinois

Application December 19, 1933, Serial No. 703,094
Renewed December 30, 1935

3 Claims. (Cl. 4—70)

My invention is concerned with plumbing systems, and more especially with such a system where a vacuum breaker, so-called, is used for the prevention of back siphonage through flush valves used on water-closet bowls, bed-pan closets, bidets, bed-pan washers, slop sinks and any other type of fixture that flush valves may be used on, or on any sterilizing tank or receptacle where the supply pipe or hose is submerged in the fluid.

It is well known that in the ordinary plumbing system, where a supply pipe rises through several floors, a vacuum may be created therein, for instance, by shutting off the water supply and opening faucets, valves, etc., or flushing closets at a lower level. When this occurs, the water will siphon out of the water-closet bowl, bed-pan closet, bidet, bed-pan washer or slop sink, when the bowl is clogged through stoppage and the water level is above the holes in the rim of the bowl. It will also occur on side spud closet bowls where the closet spud is partially or completely submerged in the water seal, which is the normal water level in the closet bowl. When back siphonage occurs, it pollutes the water in the supply line.

In carrying out my invention in the preferred form shown herein, and where it is used in connection with a flush valve, I employ as a part of the conduit connecting the supply line with the receptacle which may be siphoned, a pipe connecting the bottom of the flush valve with the bowl, in which pipe is an aperture protected by means in the pipe so that it permits the downward passage of the water from the supply pipe through the flush valve and down through the pipe without the possibility of any of it escaping through the aperture, while said means permits the air to enter freely through the aperture in case a vacuum occurs in the supply, and thus prevents the possibility of the contents of the bowl being sucked back into the supply pipe, thereby possibly contaminating its contents.

To illustrate my invention, I annex hereto two sheets of drawings, in which the same reference characters are used to designate identical parts in all the figures, of which,—

Fig. 1 is a vertical section through one type of a flush valve having my invention applied thereto and specifically designed for use with the blow-out type of closet bowl;

Fig. 2 is a similar view of a vacuum breaker of the type shown in Fig. 1, but one where it is designed for all other type closet bowls and slop sinks; and

Fig. 3 is a view of my vacuum breaker of the

type shown in Figs. 1 and 2 as applied to the flush tank of the water-closet.

In Fig. 1, I have shown a common type of flush valve 10 with its connection 11 to a supply pipe, not shown, and with a connection pipe 12 which opens in the customary manner to the top of the ordinary closet bowl, not shown. With this type of flush valve, in case a vacuum occurs in the supply pipe, the vacuum extends through the connection 11, the chamber 13 in the valve below the diaphragm 14, through the passage 15 in the lower half 16 of the valve casing, and through the passage 17 in the upper half 18 of the valve casing, and down through the self-cleansing regulating valve 19 to the upper chamber 20, where the vacuum will tilt the relief valve 21, as indicated by its position, and then past the relief-valve seat 22, and on down through the discharge passage 23, through the connection tube 12, and thence to the closet bowl, not shown, from which it will siphon its contents under the conditions above noted if no vacuum breaker is employed.

In the form shown in Fig. 1, the connection member or tube 12 has at its upper end the horizontal flange 24 by which it is held against the annular bottom of the valve casing 16 by the connecting sleeve 25 screwed on to said bottom.

I secure in the top of the connection tube, and filling it, the water inlet member or tube 36, which has the tapered portion 37 preferably located in the horizontal plane of the air inlet apertures 34, and preferably terminating in the reduced straight portion 38, which forms a nozzle cooperating with the water outlet port of the connection member which is preferably formed by the preferably slightly flared smaller end 39 of the flaring tube 40, which has its large straight lower end 41 secured in the connection tube 12, as shown. With this construction, the water during the flushing operation passes down through the nozzle 38 and 40 through the flaring tube 40 to the bowl without the possibility of any of the water reaching the apertures 34 provided in the connection tube 12 and preferably protected by a hood 35 formed on the bottom of the connecting sleeve 25. When the vacuum occurs, the air, as indicated by the arrows, will enter the apertures 34 and pass through the annular channel 42 between the end 39 of the flaring tube 40 and the end of the nozzle 38, and pass up through the flush valve to the supply pipe, effectively breaking the vacuum. In Fig. 1 this arrangement is shown with the nozzle 38 and the end of the flaring tube 40 of the proper size to be used with the blow-out type of closet bowl, where only a small passage for the water is needed.

Naturally the action of this Venturi tube arrangement is to draw some air into the connection member through the inlets 34 and carry it down with the water through the outlet 38 during the flushing operation.

In Fig. 2, I illustrate the same identical parts, but proportioned differently, as shown, to furnish the larger passage required with the less back pressure used in other type closet bowls and slop sinks.

In Fig. 3, I have shown my invention as applied to a water-closet tank 48, in which a connection 44 to the supply pipe, not shown, has secured thereto on the interior of the tank the extension 45 of the supply pipe, which is connected to the valve casing 46 having the seat 47 for the valve 52, which has the connection shown to the float ball 48, so that when the water 50 reaches the level shown, the valve 48 will be seated, and with this type of flushing apparatus, any customary connection 54 is used with an operating handle, so that as the connection 54 is lifted, the valve 52 will be lifted from its seat 53, permitting the contents of the tank to flow rapidly down through 25 the discharge outlet 54 to the closet. These flush valves ordinarily have the valve casing 46 provided with an opening in which is secured the tube 55 extending downwardly nearly to the bottom of the tank so as to deliver the supply of water there- 30 to after flushing without any unnecessary noise or splashing. In the utilization of my invention, this tube 55 corresponds in its operation to the connection tube 12 shown in Figs. 1 and 2, and, like it, I provide the tube 55 with the apertures 34 and 35 the tubes 36 and 48 constructed and operating just the same as they are described in connection with Figs. 1 and 2.

While I have shown and described my invention as embodied in the form which I at present consider best adapted to carry out its purposes, it will be understood that it is capable of modification, and that I do not desire to be limited in the interpretation of the following claims except as may be necessitated by the state of the prior art.

45 What I claim as new, and desire to secure by Letters Patent of the United States, is:

1. As a new and useful article of manufacture, a connection tube having an aperture in its side and having a tube secured in and filling it above the aperture, which tube terminates in a reduced nozzle below the aperture, and a flaring tube having its smaller end co-operating with the nozzle and its large end engaging the walls of the connection tube.

55 2. As a new and useful article of manufacture, a connection tube having an aperture in its side and having a tube secured in and filling it above the aperture, which tube terminates in a reduced nozzle below the aperture, a flaring tube having its smaller end co-operating with the nozzle and its large end engaging the walls of the connection tube, and a hood surrounding the connection tube protecting the aperture.

3. In a plumbing system, means for preventing back siphoning, which consists of a conduit leading to the bowl and having an aperture therein, and a tube secured therein and filling it above the aperture which tube terminates in a reduced nozzle below the aperture, and a flaring tube having its smaller end co-operating with the nozzle leaving an annular passage between them and its large end engaging the walls of the conduit.

4. In a plumbing system, a tube through which water from a supply pipe is discharged downwardly having an aperture in its side and having a second tube terminating in a reduced nozzle below the aperture secured therein and filling it above the aperture, and a third tube having its smaller upper end co-operating with and receiving the discharge from the nozzle and its lower end engaging the walls of the first tube.

5. In a plumbing system, means for preventing back siphoning, which consists of a conduit leading to the bowl and having an aperture therein, and a tube secured therein and filling it above the aperture, which tube terminates in a reduced nozzle below the aperture, and a member projecting from and closing the lower end of the tube except for an opening in said member through which the water is discharged, which opening co-operates with the nozzle to form an annular passage through which air is drawn upwardly in breaking a vacuum.

6. In a plumbing system, a tube through which water from a supply pipe is discharged downwardly having an aperture in its side and having a second tube terminating in a reduced nozzle below the aperture secured therein and filling it above the aperture, and a member projecting from and closing the lower end of the tube except for an opening in said member through which the water is discharged, which opening co-operates with the nozzle to form an annular passage through which air is drawn upwardly in breaking a vacuum.

7. In a plumbing system, means for preventing back siphoning which consists of a member extending toward the article to be flushed having an air inlet therein and a water outlet port of lesser diameter than that of the interior of the body of the member, and an inlet member secured therein having its internal cross-sectional area reduced to form a nozzle through which the water is discharged forwardly, the air inlet being in a portion of the member surrounding and spaced away from the nozzle, and the nozzle cooperating with the water outlet port to form a passage through which air from the inlet is sucked forwardly with the water when flushing and through which air is passed rearwardly through the nozzle in breaking a vacuum.

8. A plumbing system as described in claim 7 in which the air inlet is protected by a hood extending downwardly thereover.

WILLIAM C. SHANLEY.
